UNITED STATES PATENT OFFICE.

JOHN W. BAILEY, OF JERSEY CITY, NEW JERSEY, ASSIGNOR TO THE UNION LEAD AND OIL COMPANY, A CORPORATION OF NEW JERSEY.

METHOD OF PRODUCING LEAD CARBONATE.

SPECIFICATION forming part of Letters Patent No. 709,955, dated September 30, 1902.

Application filed January 29, 1901. Serial No. 45,209. (No specimen.)

To all whom it may concern:

Be it known that I, JOHN W. BAILEY, a citizen of the United States, and a resident of Jersey City, in the county of Hudson and State of New Jersey, have invented an Improved Method of Producing Lead Carbonate, of which the following is a full, clear, and exact specification, reference being had to the accompanying drawings, which form a part hereof.

The invention relates to a method of manufacturing or producing lead carbonate, or what is commonly known as "white lead," which is automatic and continuous in its character, and the features of my improved method are addressed to the organized treatment of the material employed at certain periods of the process, with definite relation to the peculiarities of the material at different stages of the manufacture and to the chemical action which is to take place therein.

The object of the invention is to overcome certain defects or imperfections in the treatment of the lead heretofore employed, which by reason of the peculiar characteristics of the material interfere with the thoroughness of the conversions and tend to prevent homogeneity in the product.

A further object of the invention is to produce the said white lead quickly and economically and to furnish a product which is superior in quality to that which is made by the methods or apparatus now in use.

The most desirable form in which the metallic lead can be presented to the attack of the so-called "corroding reagent" is that of "fiber," as it is commonly termed, which is necessarily obtained in a more or less matted mass, consisting of the intertwined hairs or fibers as they come through the delivery-apertures of the comminuting apparatus. It is found that this mass if subjected to any handling whatever, or even if allowed to stand for an undue length of time, is liable to become irregularly compacted owing to the very soft character of the metal and the lack of any definite structure in the mass. The result is that the lead does not afford uniform access for the corroding reagents, so that local aggregations of uncorroded metal are developed, and the product not only lacks homogeneity,

but requires special treatment for the separation of the metallic residuum. In some measure the same difficulty is met with when other forms of comminuted lead are employed besides that of fiber. With these also it is desirable that the individual particles should preserve, as far as possible, whatever superficial porosity they initially possessed and that the mass of soft particles should not be compacted by handling.

My invention comprises first a method of producing lead carbonate which consists in so comminuting metallic lead that it may be maintained in an uncompacted condition, conveying the lead in this condition into a corroding-chamber, and without substantial disturbance subjecting the lead therein to the action of a suitable corroding-gas, whereby compacting of the comminuted lead is avoided and a uniform attack of the corroding agent is facilitated.

My invention also comprises a method of producing lead carbonate which consists in feeding comminuted lead onto a suitable carrier, conveying the lead in this condition without substantial disturbance into a corroding-chamber, causing it to move through said chamber without substantial disturbance, and subjecting it therein to the action of a suitable corroding-gas. In the best form of my invention a moistening agent, preferably a solution of acetic acid in water, is applied to the lead without disturbing the lead on its way to the corroding-chamber. The best method known to me of carrying out this particular step of the process is to cause the lead to pass through a bath containing the moistening agent before it enters the corroding-chamber.

My invention also comprises the feeding of the comminuted lead or lead fiber onto a suitable carrier in waves or masses wholly or partly separated from one another. These waves or masses preferably contain predetermined or regulated quantities of the comminuted lead.

My invention also comprises a method of producing lead carbonate which consists in comminuting the lead so as to form it into lead fiber, feeding the lead fiber directly from the comminuting device onto a suitable car-

rier in waves or wave-like masses, conveying the lead in this condition without substantial disturbance through a bath containing a moistening agent or applying the moistening agent to the lead in some other way without disturbing the lead, then conveying the lead without substantial disturbance through the air for a certain distance and into a corroding-chamber and causing the lead to move through said chamber without substantial disturbance, and subjecting it therein to the action of a suitable corroding-gas. I prefer to comminute the lead by heating it to a temperature only slightly above its melting-point and then causing it to flow through one or more fine orifices, so as to form it into lead fiber.

My invention also comprises the feeding of regulated or predetermined quantities of the comminuted lead into the corroding-chamber successively—that is to say, one after another and at suitable intervals—withouts substantial disturbance of the lead and causing the lead in the corroding-chamber to move in said chamber while each fresh supply of lead is being fed thereto and to remain at rest during the intervals between the feeding operations and subjecting the lead while in said chamber to the action of a suitable corroding-gas, such as carbonic-acid gas, whereby a certain predetermined or desired quantity of the comminuted lead can be fed into the corroding-chamber each day and can be subjected in the said chamber for a sufficient length of time to the action of the corroding-gas and can be discharged from the said chamber when the corroding action is substantially complete.

My invention further comprises the method of producing lead carbonate which consists in conveying comminuted lead through the corroding-chamber and at suitable intervals inverting or turning over the lead in a uniform manner and without such irregular disturbance as would tend to injuriously compact it, whereby new surfaces are presented to the attack of the gas in a definite or organized manner.

My invention also comprises applying a moistening agent, preferably acetic acid in water, to the lead in the corroding-chamber so as not to disturb or compact the lead.

My invention also comprises certain other steps or combinations of steps in the treatment of the lead, which will be hereinafter fully described and claimed.

In the accompanying drawings I have shown an apparatus especially suitable for carrying out the method herein described, although it will be apparent that my improved method may be carried out by means of a great variety of apparatus.

In the drawings similar numbers refer to similar parts of the apparatus.

Figure 1 is a vertical sectional view of the apparatus referred to. Fig. 2 is a vertical section of the corroding-chamber taken on the line *a b* of Fig. 1. Fig. 3 is a longitudinal sec-

tion of the carriers. Fig. 4 is an enlarged view illustrating the manner in which the lead fiber is fed onto the carrier. Fig. 5 is an enlarged view illustrating the manner in which the lead fiber passes from one carrier to another carrier in the corroding-chamber.

Referring to the drawings, 1 is one of a series of melting-pots for melting the pig-lead and converting it into fiber or finely comminuted or "shotty" lead. 2 is a discharge-pipe leading from the bottom of said melting-pot and provided with a suitable valve 3.

4 is a plate provided with fine openings or orifices and placed at the outlet end of the pipe 2, through which the molten lead is forced by means of the weight of the column of lead in the melting-pot 1.

5 is a feed-hopper into which the lead fiber passes after it has been forced out through the openings in plate 4. This hopper is made of sheet-iron or other suitable material and suspended at its upper end on the rock-shaft 8 and so arranged that it can swing for a short distance back and forth, as represented in dotted lines in Fig. 1. Any suitable device may be used for giving the rocking motion to the said hood.

9 is a carrier in the form of a continuous belt, preferably made about eight feet wide. It is stretched upon and carried by the pulleys 10 and the idlers 11. This belt 9 is preferably made of wood slats^{9a}, held together by links or belting^{9b}, and may be covered with wire-cloth^{9c} or other suitable material, the purpose of this construction being to permit the belt to pass easily over the pulleys and the idlers and at the same time to permit the corroding-gas to pass easily through the belt, so as to reach every part of the comminuted lead which is being carried by the belt. The belt is moved by sprocket-wheels on the pulleys 10.

12 is a box containing a regulated solution of a moistening agent, preferably acetic acid and water, supplied automatically and maintained at a given level from the tank 13. The tank 13 is kept suitably supplied with acidulated water and is connected by means of the pipe 14 with the box 12.

15 represents a float-valve device arranged in the box 12 and adapted to open and close the discharge-valve in the pipe 14, thereby maintaining the solution in the box 12 at any desired level.

The belt 9 after receiving its charge of lead fiber passes underneath the large idler 11 and the lead is thereby made to pass through the bath in the box 12, as a result of which the stock under treatment is wet to properly acidify it before subjecting it to the action of the air and the corroding-gas. The belt 9 is preferably made several hundred feet long—say from three hundred to six hundred feet—so as to give it a capacity of several tons per day.

16 is an apron for conducting the drippings from the belt 9 back into the tank 12.

17 is a corroding-chamber, which may be, say, eight or nine feet wide and from one hundred to three hundred feet long and into which the belt 9 feeds the lead fiber 6 in the manner illustrated in Fig. 1. The opening through which the belt 9 passes into the corroding-chamber is preferably provided with a flexible curtain 18, adapted to readily yield to permit the passage of the belt and comminuted lead without disturbing the lead, but to prevent the escape of any considerable quantity of the corroding-gas.

19 represents a series of belts or conveyers suitably mounted upon and carried by rollers or pulleys 20. These belts are staggered with reference to one another—that is to say, the uppermost belt 19 projects beyond the belt 9, as shown at the left-hand side in Fig. 1—so that the comminuted lead may fall from the belt 9 upon the uppermost belt or conveyer 19 and be carried backward across the corroding-chamber. The second belt 19, counting from the top, projects beyond the belt 19 immediately above it at the right-hand side. 25 The third belt 19, counting from the top, projects beyond the belt 19 just above it on the left-hand side, and so on down through the series of belts or conveyers. The pulleys or rollers 20 are provided with sprocket-wheels 30 to drive the belts 19 and also at one end of the corroding-chamber with driving-gears 21. (See Figs. 1 and 2.) The pulley 10 at the upper end of the corroding-chamber on the left side, as shown in Fig. 1, is also provided with a driving-gear 21. These gears 21 preferably mesh with one another and are connected in any suitable way with a driving-shaft. It will be evident that by means of this series of gears adjoining belts will be 40 driven in opposite directions, which will cause the belts to continually carry the comminuted lead back and forth from one side of the corroding-chamber to the other, the comminuted lead falling from each belt to the belt below, 45 and so on until it reaches the lowest belt of the series. The belts 19 are open-meshed belts, such as could be made of wood slats held together by links and covered with any open-mesh cloth adapted to permit the 50 corroding-gas to pass freely through the belts.

22 22 are sprinkling-pipes for sprinkling the stock under treatment as it passes through the corroding-chamber. These pipes are connected with any suitable source of supply and 55 extend across the chamber, being of substantially the same width as the belts 19, and are provided with perforations through which the acidulated water is sprinkled or sprayed on the stock which is under treatment. As 60 many of these pipes may be employed as are thought desirable or necessary. The supply of moistening liquid to these pipes may be automatically controlled, as by an automatic governor 35, so that when belts 19 are in motion moistening fluid will be supplied to these pipes, but will be shut off when the belts are at rest.

23 is a pipe or conduit for supplying the steam and corroding-gas—namely, carbonic-acid gas—and for distributing them through 70 the bottom of the corroding-chamber. This pipe is provided with perforations on its upper side and is connected with any suitable source of supply of the said steam and corroding-gas.

75 24 is a sump or receptacle for catching the drippings from the moving belts 19 and is preferably shaped as shown in Fig. 2.

25 25 are supporting-rollers for supporting the belt 9 and also the belts 19. Any number of these may be used for this purpose.

26 is a pipe for conveying the waste gases from the corroding-chamber.

27 27 (see Fig. 2) are tracks or ways which are traveled by the links at the ends of the 85 slats, of which the belt 9 and the belts 19 are made. These tracks are simply to guide the belts and cause them to move properly over the rollers 20.

28 is a chute for receiving and delivering 90 the corroded product to the wash-machine.

29 is a revolving wash-machine for separating the corroded metal from the portion of the stock that has not been corroded, by means of which the latter—that is to say, the 95 waste product—is thrown out and collected for further treatment.

30 is a hopper-bottomed tank in which the wash-machine works and the bottom of which receives the corroded product. The wash-machine consists of a reel which is covered with a fine brass-wire screen or other suitable material and adapted to permit the white lead to pass through the meshes or perforations of the same while preventing the 105 uncorroded product from escaping. The tank 30 is provided with sufficient water to partly submerge the lower side of the reel. The tank 30 is provided with a pipe 31, through which the white lead which is suspended in the water can be pumped to the 110 drying-room. The rear end of the reel is provided with diaphragms or partitions 32, extending part of the distance from the circumference of the reel toward the axis and adapted to carry the uncorroded portions of the material to the upper side of the reel and to dump them on the inclined chute 33, from which they drop into the receiver 34 for the 115 waste products.

120 My improved process is carried out as follows: Metallic lead is melted in the melting-pots 1 by any suitable means. In the best application of my invention the lead is heated to a temperature only slightly above the melting-point and is caused to flow through one or more fine orifices in the plates 4. It solidifies as soon as it reaches the air, forming a thread-like product in structure like wool and known as "lead fiber." I prefer to force 125 the lead through the fine orifices in the plates 4 by means of the pressure of a column of lead in the melting-pots 1 of sufficient height to force the molten lead through said orifices.

If the metallic lead is heated to a higher degree of temperature, it will break into a fine shotty condition. Broadly considered, my invention is not limited to the use of lead fiber, although it is particularly adapted and designed to be applied to lead which is comminuted into the form of fiber. The hopper 5 is given a rocking motion, swinging between the positions indicated in Fig. 1, one 10 being in a full line and the other in a broken line. The lead fiber slides down through the hopper 5, and by means of the rocking motion of the hopper 5 is fed onto the carrier-belt 9 in masses or waves wholly or partly separated, 15 each mass or wave containing a regulated quantity of the comminuted lead, or with a waving action which disposes the fiber in a mat, having comparatively uniform convolutions which stand in a more or less upright position, as illustrated in Fig. 4. This permits the formation of a comparatively thick mat of fiber, with something in the nature of a structural organization, that resists the tendency of such a body to sink or compact itself together. One result of thus disposing the lead 20 into more or less independent waves or undulations is that the moistening agent, the air, and the corroding-gas are given more complete access to the parts thereof and the corrosion is consequently more thorough. The belt or carrier 9 then carries the comminuted lead without substantial disturbance through the bath containing the agent which is employed to make the preliminary attack on the 25 metal. I prefer to use a solution of acetic acid and water for this purpose, although any other suitable agent may be employed, provided it is adapted to accomplish a similar result. This bath is contained in the box 12, 30 which holds a regulated solution of acetic acid and water. This solution is preferably of a strength of about one part of twenty-six-per-cent. acid to eight parts of water. The supply of the solution in said bath is automatically maintained. An ample supply of the solution at the proper strength is kept in the tank 13 and is fed to the box 12 through the pipe 14 and maintained at a given level in the box 12 by means of the float-valve device 35 15. After the metallic lead has been thus passed through the bath of the moistening agent it is carried by the belt 9 without substantial disturbance through the air and into the corroding-chamber 17 in the manner indicated in the drawings. While passing through the air to the corroding-chamber the lead or a part of it is oxidized and combining with the acetic acid forms acetate of lead, being thus prepared for the action of the corroding-gas. The lead passes from the belt 9 40 onto the top one of the series of belts or conveyers 19 in the manner illustrated in Fig. 5. In passing from one belt to another in this way the lead is inverted or changed in position, so as to expose new parts or surfaces to the action of the corroding-gas and without such severe or irregular disturbance as would

tend to injuriously compact it. The belt 9 and the various belts 19 are preferably made to travel at the same rate of speed, so that the 70 comminuted lead is not torn apart or compacted. Any part of the moistening solution that drips from the belt 9 on its way from the bath to the corroding-chamber falls upon the apron 16 and runs back into the bath. The 75 comminuted lead is carried back and forth through the corroding-chamber, being delivered from one belt 19 to the next lower belt 19, and during all this time is exposed to the action of the carbonic-acid gas and steam, 80 which are introduced into the chamber through the pipe 23. The lead is thus very thoroughly and uniformly corroded. At the same time the lead is kept wet or moistened by being sprinkled with acidulated water 85 through the sprinkling-pipes 22. The corroded lead is finally delivered by the lowest belt into the chute 28, from which it passes into the washing machine or reel 29. This reel rotates in the tank 30, which is provided with enough water to cover the lower portion of the reel. The water separates the fine amorphous powder, which is the lead carbonate, from the residue and carries it through the meshes of the reel into the bottom of the tank 30, from which it is pumped to the drying-room. After it has been dried it is the finished dry white lead of commerce. The uncorroded portion, which is usually not more than eight per cent., cannot pass through 90 the meshes of the wash-machine and is dropped out at the farther end into the receptacle 34 and is subjected to further treatment. The corroding-chamber having sixteen of the belts or conveyers 19 and being three hundred feet in length would give a total length of travel of about five thousand feet in the corroding-chamber before the stock under treatment would pass into the washing-machine. 95

In the best form of my improved process I feed predetermined quantities of the comminuted lead into the corroding-chamber successively at intervals. For example, I run the belt 9 for two and a half hours, causing 100 it to travel at the rate of about seven feet per minute. This belt receives about fifteen pounds of lead fiber per lineal foot if made eight feet wide. Thus I feed about one thousand feet of the comminuted lead into the 105 corroding-chamber and then stop the belts and allow the comminuted lead to remain at rest during the remainder of that day in the said corroding-chamber, where it is subjected all the time to the action of the corroding-gas. The next day a similar quantity of comminuted lead is fed into the corroding-chamber, and then the belts are again stopped, and this is continued from day to day. After four 110 days of continuous operation the belts would be nearly full and on the fifth day the machine would begin to discharge the corroded stock into the wash-machine. After this I feed a similar quantity of comminuted lead 115

into the corroding-chamber each day, and a like quantity of corroded product is discharged from the corroding-chamber each day. This would give a daily output of corroded product of about nine or ten tons, counting on an increase in weight in the corroded product of only about twenty per cent.

In my improved method the treatment of the material is so adapted to the peculiar nature of the same that the great difficulties heretofore encountered in handling the lead in the various stages of its manufacture into white lead are entirely overcome. Indeed the very characteristics of the lead which have given rise to these difficulties are availed of in my method to secure a quicker and more complete and thorough corrosion. The entire body of the lead is so completely exposed to the successive actions of the various agents employed and under such advantageous circumstances that only a very small part of the lead under treatment remains uncorroded. By causing the lead to move in or through the corroding-chamber the circulation of the corroding-gas through the pores or interstices of the lead is aided. By moistening the lead from time to time in the chamber the corrosion is greatly assisted and without any danger of compacting the lead or subjecting it to contact with impurities or dust, such as would exist if the lead had to be removed from time to time from the chamber for the purpose of being moistened.

The white lead made by this process is superior to any form of white lead heretofore produced. It has all the good qualities of lead corroded by the slow processes heretofore employed—such as body, sticking, and lasting qualities—and is superior to the products heretofore produced by the quicker processes in that it has no stains or discolorations and is not in a crystalline condition, like the old Dutch lead. It is an amorphous powder free from the usual stains and dust resulting from the processes heretofore in use. It is also superior to white lead produced by chemical precipitation, because the latter is lacking in body, is "fluffy," and will not hold its color, whereas the product of the present process does not have these defects.

In my improved method I can also regulate the percentage of carbonate and hydrate, and thus accurately control the character of the product.

It will be apparent that by means of my improved method white lead can be produced very quickly and with a minimum of labor, thus securing great economy without endangering the health of the workmen.

What I claim as new, and desire to secure by Letters Patent, is—

1. The method of producing lead carbonate which consists in so comminuting metallic lead that it may be maintained in an uncompacted condition, conveying the lead in this condition without substantial disturbance into a corroding-chamber, causing it to move

through said chamber without substantial disturbance and subjecting it therein to the action of a suitable corroding-gas whereby compacting of the comminuted lead is avoided and the uniform attack of the corroding agent is facilitated, substantially as described. 70

2. The method of producing lead carbonate which consists in so comminuting metallic lead that it may be maintained in an uncompacted condition, applying a moistening agent to the lead without disturbing the lead, conveying the lead in this condition without substantial disturbance into a corroding-chamber, causing it to move through said chamber without substantial disturbance and subjecting it therein to the action of a suitable corroding-gas whereby compacting of the comminuted lead is avoided and the uniform attack of the corroding agent is facilitated, substantially as described. 75 80 85

3. The method of producing lead carbonate which consists in so comminuting metallic lead that it may be maintained in an uncompacted condition, conveying the lead in a substantially undisturbed condition through a bath containing a moistening agent and then into a corroding-chamber, causing it to move through said chamber without substantial disturbance, and subjecting it therein to the action of a suitable corroding-gas whereby compacting of the comminuted lead is avoided and the uniform attack of the moistening and corroding agents is facilitated, substantially as described. 90 95 100

4. The method of producing lead carbonate which consists in subdividing metallic lead into a hair-like or fibrous condition, forming the lead thus comminuted into uncompacted waves or masses wholly or partly separated, applying a moistening agent to the lead without disturbing the lead, conveying the lead in this condition without substantial disturbance into a corroding-chamber, causing it to move through said chamber without substantial disturbance and subjecting it therein to the action of a suitable corroding-gas whereby compacting of the comminuted lead is avoided and the uniform attack of the corroding agent is facilitated, substantially as described. 105 110 115

5. The method of producing lead carbonate which consists in forming lead fiber into uncompacted waves or masses wholly or partly separated, applying a moistening agent to the lead without disturbing the lead, conveying the lead in this condition without substantial disturbance into a corroding-chamber, causing it to move through said chamber without substantial disturbance and subjecting it therein to the action of a suitable corroding-gas whereby compacting of the comminuted lead is avoided and the uniform attack of the corroding agent is facilitated, substantially as described. 120 125 130

6. The method of producing lead carbonate which consists in comminuting the lead so as to form it into lead fiber, forming the lead

- fiber into uncompacted waves or masses, conveying the lead in this condition without substantial disturbance through a bath containing a moistening agent, then conveying the lead without substantial disturbance through the air and into a corroding-chamber, causing the lead to move through said chamber without substantial disturbance and subjecting it therein to the action of a suitable corroding-gas, substantially as described.
7. The method of producing lead carbonate which consists in comminuting the lead so as to form it into lead fiber, forming the lead fiber into uncompacted wave-like masses, applying a moistening agent to the lead without disturbing the lead, conveying the lead in a substantially undisturbed condition through the air for a certain distance and then into a corroding-chamber, causing it to move through said chamber without substantial disturbance, applying a moistening agent to the lead in said chamber and subjecting the lead in said chamber to the action of a suitable corroding-gas, substantially as described.
8. The method of producing lead carbonate which consists in so comminuting the lead that it may be maintained in an uncompacted condition, applying a moistening agent to the lead without disturbing the lead, forwarding predetermined quantities of the lead without substantial disturbance into the corroding-chamber successively and at intervals, causing said lead to move in said corroding-chamber without substantial disturbance while each fresh supply of lead is being fed into said chamber and to remain at rest during the intervals between the forwarding operations, subjecting the lead in said chamber to the action of a suitable corroding-gas, substantially as described.
9. The method of producing lead carbonate which consists in conveying comminuted lead through a corroding-chamber and at suitable intervals inverting the lead therein without compacting the same, and subjecting the lead in said chamber to the action of a suitable corroding-gas whereby new surfaces are presented to the attack of the gas in a definite and organized manner, substantially as described.
10. The method of producing lead carbonate which consists in so comminuting the lead that it may be maintained in an uncompacted condition, applying a moistening agent to the lead without disturbing the lead, conveying the lead in this condition without substantial disturbance into a corroding-chamber, causing the lead to move through said chamber without substantial disturbance and at suitable intervals inverting the lead and subjecting it in said chamber to the action of a suitable corroding-gas, substantially as described.
11. The method of producing lead carbonate which consists in so comminuting the lead that it may be maintained in an uncompacted condition, applying a moistening agent to the

lead without disturbing the lead, conveying the lead in this condition without substantial disturbance into a corroding-chamber, causing the lead to move through said chamber without substantial disturbance and at suitable intervals inverting the lead, applying a moistening agent to the lead in said chamber at intervals without disturbing the lead, and subjecting it in said chamber to the action of a suitable corroding-gas, substantially as described.

12. The method of producing lead carbonate which consists in arranging the comminuted lead so as not to compact it but to present an extended surface to the action of the different agents employed, applying to it in this condition a solution of acetic acid and water, passing it without substantial disturbance through the air to the corroding-chamber so as to form acetate of lead, causing it to move without substantial disturbance in said chamber for a period of time and exposing it during said time to the action of a current of carbonic-acid gas, then causing it to fall through said chamber for a sufficient distance to rearrange the mass without compacting it so as to expose new surfaces to the corroding-gas, then causing it to move again through said chamber and repeating this operation until the lead is sufficiently corroded, substantially as described.

13. The method of producing lead carbonate which consists in arranging the comminuted lead so as not to compact it but to present an extended surface to the action of the different agents employed, applying to it in this condition a solution of acetic acid and water, passing it without substantial disturbance through the air to the corroding-chamber so as to form acetate of lead, causing it to move without substantial disturbance in said chamber for a period of time and exposing it during said time to the action of a current of carbonic-acid gas, then causing it to fall through said chamber for a sufficient distance to rearrange the mass without compacting it so as to expose new surfaces to the corroding-gas, then causing it to move again through said chamber, moistening it at intervals in said chamber with a solution of acetic acid and water and repeating this operation until the lead is sufficiently corroded, substantially as described.

14. The method of producing lead carbonate, which consists in so comminuting metallic lead that it may be maintained in an uncompacted condition, conveying the lead in this condition into a corroding-chamber, and without substantial disturbance subjecting the lead therein to the action of a suitable corroding-gas, whereby compacting of the comminuted lead is avoided and the uniform attack of the corroding agent is facilitated.

15. The method of producing lead carbonate, which consists in so comminuting metallic lead that it may be maintained in an uncompacted condition, conveying the lead in

this condition into a corroding-chamber, applying a moistening agent to the lead while in the corroding-chamber, and without substantial disturbance subjecting the lead in the 5 corroding-chamber to the action of a suitable corroding-gas, whereby compacting of the comminuted lead is avoided and the uniform attack of the corroding agent is facilitated.

16. The method of producing lead carbon-
ate, which consists in subdividing metallic
lead into a fine hair-like or fibrous condition,
conveying the lead in this condition without
substantial disturbance into a corroding-
chamber, and without substantial disturbance
subjecting the lead in the corroding-
chamber to the action of a suitable corroding-
gas, whereby compacting of the comminuted
lead is avoided and a uniform attack of the
corroding agent is facilitated.

17. The method of producing lead carbon-

ate, which consists in subdividing metallic
lead into a fine hair-like or fibrous condition,
conveying the lead in this condition without
substantial disturbance into a corroding-
chamber, applying a moistening agent to the 25
lead while in the corroding-chamber, and
without substantial disturbance subjecting
the lead in the corroding-chamber to the ac-
tion of a suitable corroding-gas, whereby
compacting of the comminuted lead is avoided 30
and the uniform attack of the corroding agent
is facilitated.

In testimony whereof I have signed my
name to this specification in the presence of
two subscribing witnesses.

JOHN W. BAILEY.
